* cited by examiner

Primary Examiner — Rosemary K Tarca*Assistant Examiner* — Christy Nemeth(74) Attorney, Agent, or Firm — Knobbe, Martens, Olson & Bear, LLP(57) CLAIM

The ornamental design for snuff pouches in a snuff box, as shown and described.

DESCRIPTION

FIG. 1 is a top, back and side perspective view of snuff pouches in a snuff box embodying my new design; and, FIG. 2 is a top view thereof.

Broken lines are used to illustrate features of the snuff box which form no part of the claimed design.

1 Claim, 2 Drawing Sheets*FIG. 1*
